Primary Examiner—Brian N. Vinson(74) *Attorney, Agent, or Firm*—Burns, Doane, Swecker & Mathis, L.L.P.(57) **CLAIM**

The ornamental design for a paper dispenser, as shown and described.

DESCRIPTION

FIG. 1 is a front, side perspective view of a paper dispenser showing my new design;

FIG. 2 is a side perspective view thereof, with the casing portion being shown in an open position;

FIG. 3 is a rear perspective view of the casing portion of the paper dispenser shown in FIG. 1, with the wall mounting portion being removed for clarity;

FIG. 4 is a front, side perspective view of the wall mounting portion of the paper dispenser shown in FIG. 1, with the casing portion being removed for clarity;

FIG. 5 is a bottom perspective view thereof;

FIG. 6 is a top perspective view thereof;

FIG. 7 is a rear perspective view thereof;

FIG. 8 is a front perspective view of the rear base platform of the wall mounting portion shown in FIGS. 4-7;

FIG. 9 is a front perspective view thereof, including the position plate in a first position;

FIG. 10 is a front perspective view thereof, including the position plate in a second position;

FIG. 11 is a side perspective view of the paper holder of the wall mounting portion shown in FIGS. 4-7;

FIG. 12 is a bottom perspective view thereof;

FIG. 13 is a front perspective view of the position plate of the wall mounting portion shown in FIGS. 4-7; and,

FIG. 14 is a rear perspective view thereof.
